CHARLES H. KESTENMAN, OF PROVIDENCE, RHODE ISLAND, ASSIGNOR TO KESTENMAN BROS. MFG. CO., OF PROVIDENCE, RHODE ISLAND, A CORPORATION OF RHODE ISLAND.

EXPANSIBLE BAND OR BRACELET.

Application filed May 23, 1927. Serial No. 193,530.

This invention relates to improvements in expansible metal bands, chains or linkages for use as articles of jewelry, such as bracelets, necklaces, girdles and the like.

5 A principal object of the invention is to provide an improved article of manufacture of the type specified comprising articulated links or chain-elements which are adapted to flex, one in relation to another, and to slide longitudinally relatively to each other to allow expansion in the length of the bracelet or other article.

10 Another object of the invention is to provide an expansible band, chain or linkage in which the individual links may be easily disconnected and detached to shorten the bracelet or other article and to permit the insertion of additional links to lengthen it.

15 Another object of the invention is to provide an article of the type specified in which the links may be constructed from sheet-metal blanks struck up in dies and assembled in interconnected relation without the use of pivots, rivets or soldered joints.

20 Another object of the invention is to provide an article of the type specified which is more economical to manufacture, of stronger construction and proof against breakage or damage in use.

25 Further objects of the improvement are set forth in the following specification which describes a preferred embodiment of the invention as illustrated by the accompanying drawings. In the drawings:

30 Fig. 1 is a perspective view illustrating the general appearance of the band or linkage as adapted for use as a watch-bracelet and showing it with its links in contracted and flexed relation;

35 Fig. 2 is an enlarged bottom plan view showing several of the connected links and illustrating a portion thereof in section to disclose the resilient expansion-means enclosed therein;

40 Fig. 3 is an enlarged side view of several of the links with two of them shown in section on line 3—3 of Fig. 2 and with one end link shown with its clasp or hook opened;

45 Fig. 4 is an enlarged cross-sectional view of 50 a pair of outer and inner links showing the relation between the slide link and the outer link and the means for holding the latch member of the inner link in place;

Fig. 5 is a perspective view showing the two parts of the outer or main link before they are assembled in connected relation; and

55 Fig. 6 is a perspective view showing the two parts of the inner or slide link before assembling.

60 My improved band, chain or linkage consists in general of a series of main elements or outer link-members 2 of the box type assembled with inner connecting-links or slides 3 which are telescoped within the main links and held in contracted relation by resilient 65 means, such as the springs 4, to adapt them to be extended to provide for the expansion of the band or chain as a whole. The main links 2, shown in inverted position in Figs. 2, 3 and 5, comprise relatively flat top-plates 6 with 70 sides 7 bent downwardly therefrom and folded inwardly to provide the right-angled bottom-strips or longitudinal flanges 8.

75 In the present invention the outer or main link 2 is of substantially the same construction as that shown in my prior application for United States Letters Patent Serial No. 160,235, filed January 10, 1927. Assembled with each outer or main link 2 is a rectangular frame 10, shown in detail in Fig. 5, and the method of constructing this element and securing it in place in the main link forms one 80 of the features of the present improvement.

The frame 10 may be constructed from a relatively narrow strip of sheet-metal bent into 85 rectangular shape to form parallel sides 11 adapted to be enclosed within the sides 7 of the main link 2 with the bottom-flanges 8 thereof overlapping their edges. The two 90 sides 11 are connected at one end by a somewhat narrower cross-strip 12, and a similar cross-bar is formed in two parts at the opposite end of the frame with its sections 13 and 14 folded inwardly from the sides 11. The sections 13 and 14 are of less width than the 95 sides 11 and meet in a tongue and groove joint 15, as shown in Fig. 5. This improved form 100 of construction provides a particularly strong and rigid frame and adapts the whole element to be manufactured as a stamping bent up from a continuous strip with all of its parts integral.

105 Projecting from the edges of the sides 11 of the frame 10 are suitable lugs 16 which provide means for securing the frame 10 in place within the sides of the main links 2.

For this purpose the bottom-flanges 8 on the main links 2 are punched with apertures 17 within which the projections or lugs 16 are received when the flanges are bent across the edges of the sides of the frame 10. In this way the flanges 8 hold the frame 10 in place laterally of the main links 2 while the lugs 16 lock in the apertures 17 to secure the frame 10 from longitudinal displacement.

10 The inner slide link 3 is constructed in two parts of substantially the same form as disclosed in my co-pending application for United States Letters Patent Serial No. 125,233, filed July 27, 1926. As shown in detail in Fig. 6, the main portion of the slide link 3 consists of a flat top-plate 18 which is bent or curled around at one end to form a hook 19 terminating in a beak 21. The projecting beak 21 is slightly narrower than the main portion of the top-plate 18, as shown more particularly in Fig. 2. The opposite end of the top-plate 18 is bent or folded at right-angles to form a cross-strip or flange 22. The cross-strip 22 is cut away or reduced 20 in width at its ends to form shouldered ledges 27 for a purpose as later explained.

15 The other cooperating part of the slide link 3 consists of a plate-like tongue or latch 23 bent over at one end to form a right-angled strip or flange 24. The flange 24 is adapted to abut the side of the end-strip or flange 22 on the top-plate 18 with the opposite free end of the latch 23 held against the edge of the beak 21 of the hook 19. It will be noted that 25 the ends of the flange 24 project beyond the sides of the latch or tongue 23 to provide ears 25 conforming to the narrowed end portions 27 of the flange 22 on the top-plate 18, these parts being of suitable width to adapt 30 them to slide freely in the space between the top-plate 6 and the bottom-flanges 8 of the main or other link 2.

35 Referring particularly to Figs. 2, 3 and 6, it is also to be observed that the tongue or latch 23 is formed with ears 26 projecting from its lateral edges adjacent the ears 25. The ears 26 are crimped or bent downwardly to adapt them to engage in under the bottom-flanges 8 of the main link 2 when the inner slide link 3 is assembled with the outer or main link, this inter-engagement being illustrated most clearly in Fig. 4 of the drawings. The ears 26 hold the latch 23 in alignment 40 with the edge of the beak 21 on the hook 19 and prevent it from canting or rocking outwardly therefrom.

45 The spring 4, previously referred to, is composed of relatively flat helical coils to adapt it to be enclosed between the top-plate 18 and the latch or tongue 23 of the slide link 3, one end of the spring abutting against the flange 24 on the latch to hold the latter against the end-strip or flange 22 on the top-plate 18, while the opposite end of the spring bears against the two-part end-bar

50 formed by the sections 13 and 14 of the frame 10. The spring 4 thus acts to hold the slide link 3 telescoped within the main link 2 in the manner illustrated by the showing of the center link of the series in Figs. 2 and 3.

55 The bracelet, chain or other articulated article is produced by assembling the several elements above described in the manner as next explained: The parts of the slide link 3 are first assembled with the frame 10 and spring 4. The frame 10 is placed in position with its cross-bar 13, 14 laid across the top-plate 18 of the slide link in under the beak 21 of the hook 19. The spring 4 is then placed in position with one end bearing against the cross-bar 13, 14 and the latch 23 set in position with its end-strip or flange 24 abutting the side of the end-strip 22 and with the spring 4 holding it in this relation.

60 The several parts of the slide link 3 assembled with the frame 10 in the manner as above explained are now assembled with the outer or main link 2 by sliding them into place between the sides 7 thereof. It is to be noted that the bottom-flanges 8 on the main link 2 are not initially bent over at right-angles to the sides 7 but are left upstanding at an angle of substantially forty-five degrees thereto. After the slide link 3 has been slid into position within the main link 2 with the sides 11 of the frame 65 16 abutting the sides 7 on the outer link the flanges 8 are bent over and their apertures 17 engaged with the lugs 16 to hold the frame 10 longitudinally with respect to the outer link 2. When the bottom-flanges 8 are bent over into the position illustrated in Figs. 3, 4 and 5 they will bear against the ledges 27 at the 70 ends of the end-strip 22 on the inner link 3 and also against the edges of the ears 25 on the latch 23 to hold these parts from displacement laterally of the link 2. The bottom-flanges 8 will also overlap the ears 26 on the latch or tongue 23 to maintain this latter part in position extending between the edges of the flanges 8 and flush therewith as regards the 75 flat bottom surface of the assembled links.

80 After the pairs of outer and inner links have been assembled in the manner as above explained they are joined together in a chain or linkage by engaging the hooks 19 on the inner slide links 3 with the cross-bars or bails 12 at the ends of adjacent outer links 2. The links are coupled together by drawing the slide links 3 outwardly as shown at the right in Figs. 2 and 3 against the tension of the springs 4. When the inner slide link 3 is extended in this manner the compression of the spring 4 will permit the tongue or latch 23 to be canted or rocked away from the beak 21 of the hook 19, as shown at the right in Fig. 3, so that the bar 12 may be hooked thereinto. A plurality of links may thus be assembled in series to form any desired length of chain, or to provide a bracelet, necklace, girdle or other article of jewelry, and any certain links

may be detached to shorten its length or other links added to extend it.

When the links are assembled to form a watch-bracelet two sections of links are employed with a narrower connecting link 27 joining the sections together as shown in Fig.

1. The opposite ends of the two sections are usually provided with clasps 28 which may be of substantially the same construction as the main links, with suitable means at their ends for connecting them to the bails on the sides of a wrist-watch.

It has been noted that the present invention embodies a construction of the main link 2 substantially the same as that disclosed in my prior application for patent Serial No. 160,235, previously referred to, but it is to be observed that in the improvement herein described the frame 10 is made in one piece. Furthermore, through the present improved construction the frame 10 is made stronger and more rigid and its method of connection with the main link 2 also renders the complete article more durable and serviceable in use.

25 As a further feature of improvement the slide link 3 has its tongue or latch 23 provided with the laterally projecting ears 26 which engage under the bottom-flanges 8 on the main link 2 to prevent the latch from moving out of place with respect to the main part 18 of the slide link. This construction also provides for holding the latch 23 in alignment with the beak 21 of the hook 19 instead of engaging it under the end of the beak, thus providing a flat unbroken surface on the under side of the links. Another advantage of the present improvement is that the parts of the chain may be assembled more conveniently and expeditiously. Also, in operation the latch or tongue 23 for the hook 19 is moved as a whole in opening the hook to engage it with or disengage it from the bail on the next link in the series so that the latch does not have to be bent or sprung out of position for this purpose.

45 This is an improvement over previously used constructions because frequent bending of the latch is liable to weaken or break this essential part, or to cause it to assume an open position where it will not guard the hook.

50 The present improvement provides a structure which is particularly adapted for economical manufacture, the parts of the device being all formed from sheet-metal so that they may be stamped out and struck up in dies. The several parts of the chain or linkage are assembled in cooperative relation without the use of pivots, rivets, or soldered joints and in this way greater economy in the cost of manufacture is realized with less liability of derangement or getting out of order.

Having now described the structure and arrangement of the complete device in detail, what I claim as an improvement is:

1. An improved construction of link for

expansible bands, chains or linkages comprising an outer member having a top-portion with sides bent at right-angles thereto and folded inwardly to form bottom-flanges provided with apertures, and an inner rectangular rigid frame having side-strips adapted to abut the sides of the outer member and formed with projections on their edges, said frame being assembled in the outer member between the top-portion and bottom-flanges thereof with its projections engaging the apertures in the bottom-flanges to rigidly hold it in place therein.

2. In an expansible band, chain, or linkage, the combination of an outer link having a relatively flat top-portion, sides bent at right-angles thereto and folded inwardly to form longitudinal flanges, a slide link comprising a flat top slideable against the top-portion of the main link and formed with an end-strip received between the top-portion and longitudinal flanges of the outer link and a hook at its opposite end, and a separate latch for the slide link having an end-strip received between the top-portion and longitudinal flanges on the outer link and formed with a tongue extending from said end-strip flush with the edges of said flanges with its end positioned opposite the beak of the hook on the slide link and provided with projections on its sides engaging under the edges of the longitudinal flanges on the main link to support it in position to close the hook while adapting it to be manually rocked away therefrom.

3. In an expansible band, chain or linkage, the combination of an outer link having a relatively flat top-portion, sides bent at right-angles thereto and folded inwardly to form bottom-flanges provided with apertures, a substantially rectangular rigid skeleton frame constructed from a single strip of sheet-metal and inserted between the sides of the outer link with its end-bars extending across the open ends thereof and having projections engaging the apertures in the outer link to rigidly secure the frame and outer link together, a slide link adapted to slide between the sides of the outer link and having means at one of its ends for connecting it with the end-bar on the inner frame of the next adjacent main link of a series, and a spring enclosed within the slide link bearing against the end-bar on the main link to maintain said links in telescoped relation.

4. In an expansible band, chain or linkage, the combination of an outer link having a top-portion with sides bent at right-angles thereto and folded inwardly to form bottom-flanges and provided with cross-bars at its open ends, a slide link having a flat portion formed with a hook at one end and a cross-strip bent at right-angles at the opposite end, a latch member having a tongue adapted to

abut the hook on the slide link and a right-angled flange at the opposite end abutting the cross-strip on the slide and ears projecting from the sides of the tongue to engage under the bottom-flanges on the main link, and a spring enclosed within the slide link engaging at one end with the flange on the

tongue to maintain the latter in abutting relation with the cross-strip on the slide link and bearing against the cross-bar on the main link to maintain the slide link telescoped within the main link.

10

In testimony whereof I affix my signature.
CHARLES H. KESTENMAN.
